CLAIM

I claim the ornamental design for table, as shown and described.

DESCRIPTION

FIG. 1 is a side view of a table;

FIG. 2 is an opposite side view thereof;

FIG. 3 is a back side view thereof;

FIG. 4 is a front view thereof;

FIG. 5 is a front perspective view with the top in an alternate position of use;

FIG. 6 is a top plan view with the back in collapsed position; and,

FIG. 7 is a back perspective view thereof.

The broken line portion of the figure drawings is included to show portions of the article that forms no part of the claimed design.

1 Claim, 7 Drawing Sheets
